UNITED STATES PATENT OFFICE.

OTTO RICKMEYER, OF MILWAUKEE, WISCONSIN.

SPARK-PLUG.

1,132,385.

Specification of Letters Patent. Patented Mar. 16, 1915.

Application filed February 18, 1914. Serial No. 819,537.

To all whom it may concern:

Be it known that I, OTTO RICKMEYER, a subject of the Emperor of Germany, residing at Milwaukee, in the county of Milwaukee and State of Wisconsin, have invented new and useful Improvements in Spark-Plugs, of which the following is a specification.

The primary purpose of the invention is the provision of mechanical means for keeping the points of spark plugs in prime condition thereby insuring positive and certain action of the ignition system of internal combustion engines embodying an electric igniter for the gaseous mixture.

One of the chief difficulties experienced in the operation of electrically ignited internal combustion engines is due to the fouling of the points between which the spark gap is formed, such fouling resulting from a deposit of carbon upon the points thereby retarding the action of the spark.

In accordance with this invention the points of the spark plug are kept free from any matter which would tend to foul the same, such means being operated automatically either by vibration, the action of compression, explosion or intake of the fuel or from any cause which would tend to produce movement and cause the cleaning devices to move with reference to the electrodes or points, whereby any tendency of matter to accumulate upon such points is wholly counteracted and prevented.

The invention consists of a cleaner mounted upon each electrode of the spark plug in a manner to move thereon so as to remove all trace of carbon or other matter that may tend to deposit upon the electrode and interfere with the free action of the spark gap.

The invention consists of the novel features, details of construction and combination of parts, which hereinafter will be more particularly set forth, illustrated and claimed.

In the drawings hereto attached:—Figure 1 is a side view of a spark plug provided with cleaning means for the points embodying the invention. Fig. 2 is a horizontal section on the line $x-x$ of Fig. 1. Fig. 3 is a horizontal section on the line $y-y$ of Fig. 1. Fig. 4 is a perspective view of one of the cleaning devices. Fig. 5 is a view in elevation of one of the cleaning devices as seen from the side, provided with the intersecting longitudinal and transverse grooves. Fig. 6

is a view in elevation of a modification. Fig. 7 is a horizontal section on the line $z-z$ of Fig. 6. Fig. 8 is a horizontal section on the line $w-w$ of Fig. 6. Fig. 9 is a central longitudinal section of one of the cleaning devices of the modification shown in Fig. 6. Fig. 10 is a perspective view of one of the cleaning devices of the modification.

Corresponding and like parts are referred to in the following description, and indicated in all the views of the drawing, by the same reference characters.

The spark plug illustrated is of the type usually employed in the operation of internal combustion engines, utilizing an electric ignition system, such plug comprising two electrodes, 1 and 2 which are somewhat similar in formation, each being of new shape, one of such electrodes being electrically connected with the body or shell of the plug and the other being electrically insulated from the shell or body by means of the usual core. One member of each electrode constitutes the point or element of the spark gap. Each electrode is provided with a cleaning device 3 which consists of a block that is slidably mounted upon the electrode so as to prevent any accumulation of fouling matter thereon. The block or body of the cleaning device has scraping edges which come in contact with and remove any matter depositing upon the electrode. The shape or manner of constructing the cleaning device is unimportant within the purview of the invention so long as the cleaning device is mounted upon the electrode to move thereon automatically and keep the same clean or free from any matter which would ordinarily tend to foul the point and interfere with the free passage of the spark. In the preferred arrangement the cleaning device has a two-fold movement upon the electrode, the one longitudinally thereof, and the other rotary.

Inasmuch as both cleaning devices are of like formation a detail description of one will suffice for a clear understanding of each. A groove 4 is formed longitudinally in a side of the body 3 and the faces 5 adjacent the groove 4 are oppositely inclined to form scraping edges 6. The scraping edges 6 extend lengthwise of the body and operate when such body turns upon the electrode, thereby removing any matter that may deposit upon such electrode opposite the groove 4. A transverse groove 7 is formed in the body midway of its ends and

intersects with the longitudinal groove 4, thereby forming transverse scraping edges. Other scraping edges are formed at the ends of the body where such ends intersect with the sides of the longitudinal groove 4. The longitudinal groove 4 receives that part of the electrode bordering upon the spark gap. An opening 8 is formed in the body 3 and extends lengthwise thereof, parallel with the groove 4, such opening being extended transversely and formed on the arc of a circle whose center coincides with the groove 4. The opening 8 receives the other member of the electrode and determines the amplitude of the turning of the cleaning devices upon the electrode. The cleaning devices are mounted upon the electrodes so as to move freely thereon, both longitudinally and angularly, such movements being brought about automatically by the vibration or jar to which the engine is subjected when in operation. It is to be understood that the cleaning device may be moved automatically in any manner, advantage being taken of the force rendered by compression, explosion and the inrush of the gases, and such force may be supplementary to the result from shock, jar or vibration. The open sides of the longitudinal grooves 4 are arranged so as to face each other and thereby prevent obstructing the adjacent sides of the electrodes between which the spark gap is formed so that the spark may have an unobstructed passage.

In the modification shown in Fig. 6 and in the detail views thereof the electrode 9 is straight, whereas the electrode 10 has a return portion 11 in line with the electrode 9. The spark gap is formed between the points or terminals of the alining elements 9 and 11. The cleaning devices are of like formation, each consisting of a body 12 having a longitudinal opening 13 and a transverse slot 14 which intersects with the opening 13. A crimp 15 formed in the alining portion of each electrode is arranged within the slot 14 and constitutes a stop to limit the longitudinal movement of the cleaning device upon the electrode. The end of the opening 13 adjacent the spark gap is con-

tracted to form a scraping edge 16. The cleaning device is free to turn on the electrode, but has a limited longitudinal movement. A wing 17 is formed upon one side of the body 12 of the cleaning device and is intended to receive the force resulting from compression, explosion and the inrush of the gases. The cleaning devices are likewise of sufficient weight to operate effectively from vibration, shock or jar to which the engine is subjected when in service.

From the foregoing description taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention, what is claimed as new is:—

1. In a spark plug and in combination with an electrode thereof, a cleaning device mounted on such electrode and comprising a body having intersecting longitudinal and transverse openings forming a plurality of scraping edges, the transverse opening extending through and intersecting the side face of the body.

2. In a spark plug and in combination with an electrode thereof, a cleaning device mounted on such electrode and free to turn and move longitudinally thereon, such cleaning device consisting of a body having intersecting longitudinal and transverse openings forming a plurality of scraping edges, the transverse opening extending through and intersecting the side face of the body.

In testimony whereof I affix my signature in presence of two witnesses.

OTTO RICKMEYER.
